(57) **CLAIM**

The ornamental design for a doll, as shown and described.

DESCRIPTION

FIG. 1 is a perspective view of a doll showing my new design;
FIG. 2 is a front view thereof;
FIG. 3 is a rear view thereof;
FIG. 4 is a side view thereof;
FIG. 5 is the opposite side view thereof;
FIG. 6 is a top view;
FIG. 7 is a bottom view; and,
FIG. 8 is an enlarged fragmentary view showing a portion of the rear of the doll with the hair in an alternate configuration.
FIG. 8 is shown as a fragmentary view for ease of illustration. The portion of the rear of the doll that is not shown in FIG. 8 is identical to the rear of the doll shown in FIG. 3.
